(57) **CLAIM**

The ornamental design for a golf bag top and handle, as shown and described.

DESCRIPTION

FIG. 1 is a top perspective view of a golf bag top and handle as claimed herein;

FIG. 2 is a front side view thereof;

FIG. 3 is a back side view thereof;

FIG. 4 is a right side view thereof;

FIG. 5 is a left side view thereof;

FIG. 6 is a top plan view thereof;

FIG. 7 is a bottom plan view thereof;

FIG. 8 is a top perspective from the back view thereof;

FIG. 9 is a bottom perspective from the back view thereof; and,

FIG. 10 is a bottom perspective view.

The broken lines in the drawings illustrate unclaimed environmental structure.
